UNITED STATES PATENT OFFICE.

TEMPLE HERBERT COLBURN, OF MINNEAPOLIS, MINNESOTA.

SOAP-CAKE RETAINER.

1,350,784.

Specification of Letters Patent. Patented Aug. 24, 1920.

Application filed July 21, 1919. Serial No. 312,162.

To all whom it may concern:

Be it known that I, TEMPLE HERBERT COLBURN, a citizen of the United States, residing at Minneapolis, in the county of Hennepin and State of Minnesota, have invented certain new and useful Improvements in Soap-Cake Retainers; and I do hereby declare the following to be a full, clear, and exact description of the invention, such as will enable others skilled in the art to which it appertains to make and use the same.

My invention relates to retainers for cakes of soap and has for its primary object to provide such a retainer that can be easily applied to a molded cake of soap and thereafter locked to prevent its removal therefrom. By the use of the improved retainer, a cake of soap secured thereto may be suspended in a position in which it will be kept dry and sanitary to prevent waste and where it can be easily reached.

To the above end, generally stated, the invention consists of the novel devices and combinations of devices hereinafter described and defined in the claims.

In the accompanying drawings, which illustrate the invention, like characters indicate like parts throughout the several views.

Referring to the drawings;—

Fig. 1 is a perspective view of the invention yieldingly suspended from a wall bracket and supporting a cake of soap over a lavatory;

Fig. 2 is a fragmentary view principally in section of the invention applied to a cake of soap;

Fig. 3 is a side elevation of the cake of soap suspended by means of the improved retainer;

Fig. 4 is a side elevation of the cake of soap and showing the method of applying the anchor shank thereto;

Figs. 5 to 8, inclusive, are detail views in perspective, with the exception of Fig. 8, which is a sectional view, of the several units of the retainer separated in their relative relation to each other;

Fig. 9 is a perspective view of the nut-block and lock-pawl removed from the cap;

Fig. 10 is a horizontal section taken on the line 10—10 of Fig. 8;

Fig. 11 is a view of the cap in vertical section and showing the eye-forming wire applied thereto and before the same is bent into form; and

Fig. 12 is a perspective view of the cap-sealing disk removed from the cap.

The numeral 13 indicates a lavatory, secured to a wall 14, to which is also secured a wall bracket 15, having mounted thereon a supporting hook 16 that is slidably adjustable toward and from the wall. The improved retainer is yieldingly suspended from the hook 16 by a chain 17 normally held wound on a spring-actuated drum, not shown, mounted in a casing 18 suspended by three converging chains 19 swiveled to an eye 20 interlocked with the hook 16. The parts thus far described have been illustrated simply for the purpose of showing one means for supporting the improved retainer.

The improved retainer comprises an anchor shank 21, a gasket 22, a lock-washer 23, nut-block 24 permanently mounted in a cap 25 in the form of a bell having an apertured upper end in which is swiveled an eye 26 attached by a snap 27 to the chain 17. In some instances, it might be desirable, as at public lavatories, to permanently connect the eye 26 to the chain 17, so that the soap could not be stolen. The shank 21 has on one of its ends, to wit the upper, a relatively fine screw-thread 28. The lower end portion of the shank 21 is folded onto the body 25 thereof and twisted therearound to form a relatively coarse left-hand screw-thread 29. The body of the shank 21, at the junction of the lower end, is formed flat, as at 30, to receive the prongs of a screw-driver or other tool 31 by which the shank 21 may be turned to screw the same in a cake of soap.

The gasket 22 is preferably formed from rubber and has an enlarged central aperture 32 to receive the screw-threaded end 28 of the shank 21, and it also has two diametrically opposite relatively small apertures 33 to receive a pair of depending anchor pins 34 on the under side of the lock-washer 23. On the upper face of the washer 23 and concentric with the axial opening therein, is a multiplicity of circumferentially spaced ratchet teeth 35. The cap 25 is adapted to be adjustably secured to the screw-threaded end 28 of the shank 21 by means of the nut-block 24, which has screw-threaded engagement therewith. To prevent the cap 25 from being unscrewed from the shank 21, there is provided for cooperation with the ratchet teeth 35 a pawl 110

36, formed on the end of a spring 37 which normally rests upon the upper face of the nut-block 24, and is secured thereto by a rivet 38. The pawl 36 projects through a 5 segmental slot 39 formed in the nut-block 24 for coöperation with the ratchet teeth 35. The nut-block 24 is permanently and rigidly secured to and within the cap 25 by pressing the same therein against an annular 10 shoulder 40, and the lower edge of said cap below the nut-block 24 is curved outwardly and upwardly for engagement with the gasket 22.

The eye 26, as shown, is formed from a 15 piece of wire having its lower end upset at 41 to afford a head. This wire is inserted from the bottom of the cap 25 through an aperture in the upper end thereof and its head 41 locks said wire to the cap 25 20 with freedom for swivel movement. After the wire has been inserted through the apertured upper end of the cap 25, the same is bent to form the eye 26. To prevent water from getting into the cap 25 through the 25 apertured end thereof, a disk 42 is pressed into said cap and against an annular shoulder 43 formed therein just below the swivled end of the eye 26.

In applying the improved retainer to a 30 cake of soap 44, the screw-threaded end 28 of the shank 21 is pressed into the lower end of the soap cake as far as it will go, and then the said shank may be turned by applying the screw-driver 31 to the lower 35 end 30 thereof. By means of the screw-driver 31, the shank 21 may be screwed into the soap a distance sufficient to project its screw-threaded end 28 through the upper end of the cake of soap and to carry its 40 lower end 30 entirely within said cake of soap, as shown in Fig. 4. The screw-driver 31 may then be removed and the lower end of the hole in the soap formed by screwing the shank 21 therein, closed or sealed by the 45 soap removed during the process of screwing the shank 21 therein. The purpose of thus sealing the lower end of the cake of soap is to prevent water from getting therein and softening the soap around the shank 50 21 so that it will pull out of the soap cake.

The next step in applying the retainer to the cake of soap is to place the washer-like gasket 22 over the projecting end of the shank 21. The lock-washer 23 is next placed 55 on the shank with the pointed ends of its anchor pins 34 positioned in the apertures 33 in the gasket 22. The washer 23 is then pressed onto the soap and its pins 34 forced therein to lock the washer 23 to the cake of 60 soap against turning movement on the shank 21. The cap 25 is then secured to the shank 21 by screwing its nut-block 24 onto the screw-threaded end 28 of said shank until its lower edge firmly engages the gasket 22 65 and presses the same onto the soap to seal

the joint between said cap and soap and thereby prevent water from softening the soap so that the shank 21 will pull therefrom. During the final turning movement of the cap 25 onto the shank 21, the pawl 36 70 engages the ratchet teeth 35 and rides therewith over with a yielding action but interlocks therewith to prevent backward turning movement of said cap on the shank 21. By reversely forming the screw-threads 28 and 75 29, the shank 21 is locked in the soap cake against turning movement at the time the cap 25 is screwed thereon. After the cap 25 is finally secured to the shank 21, the 80 retainer cannot be removed from the soap cake until the same is completely gone, at which time the washer 23 is free to move axially on the shank 21 away from the cap 25 and thereby release the engaged ratchet teeth 35 with the pawl 36. 85

What I claim is:—

1. A soap-cake retainer comprising an anchor shank having a coarse screw thread adapting said shank to be screwed completely into one end of the soap-cake to 90 project one end thereof through the other end of the soap-cake, a cap adapted to be locked onto the projecting end of the anchor shank, and a flexible connection for the cap.

2. A soap-cake retainer comprising an 95 anchor shank having a coarse screw thread adapting said shank to be screwed completely into one end of a soap-cake to project one end thereof through the other end of the soap-cake, a cap adapted to be locked 100 onto the projecting end of the anchor shank, a flexible connection for the cap, and means for filling the opening in the soap-cake caused by the insertion of the anchor shank therein. 105

3. A soap-cake retainer comprising an anchor shank having a coarse screw thread adapting said shank to be screwed completely into one end of a soap-cake to project one end thereof through the other end 110 of the soap-cake, a cap adapted to be locked onto the projecting end of the anchor shank in different longitudinal adjustments, and a flexible connection for the cap.

4. A soap-cake retainer comprising an 115 anchor shank having a body with a relatively coarse screw-thread, one end of said shank having a relatively fine screw-thread, the body of said shank adapted to be screwed completely into a soap-cake to project 120 its screw-threaded end therethrough, a cap adapted to be locked onto the projecting screw-threaded end of the shank, and a flexible connection for the cap.

5. A soap-cake retainer comprising an 125 anchor shank having a body with a relatively coarse screw-thread, one end of said shank having a relatively fine screw-thread, said two screw-threads being reversely formed, the body of said shank adapted to 130

be screwed completely into a soap-cake to project its screw-threaded end therethrough, a cap adapted to be locked onto the projecting end of the shank, and a flexible connection for the cap.

6. A soap-cake retainer comprising a shank in the form of a relatively heavy wire having a screw-thread on one of its end portions, the body of said shank being folded 10 upon itself and bent to form a coarse screw-thread, said two screw-threads being reversely formed, the body of said shank adapted to be completely screwed into a soap-cake to project its screw-threaded end 15 therethrough, a cap adapted to be locked onto the projecting screw-threaded end of the shank, and a flexible connection for the cap.

7. A soap-cake retainer comprising an 20 anchor shank one end of which is adapted to be embedded in a soap-cake, a lock-washer on the projecting end of the shank and having an anchor pin adapted to be pressed into the soap-cake to prevent said 25 lock washer from turning, a cap having screw-threaded engagement with the projecting end of the shank, means for locking the cap to the washer to prevent unscrewing of the same therefrom when applied to 30 a soap-cake, and a flexible connection for the cap.

8. A soap-cake retainer comprising an anchor shank one end of which is adapted to be embedded in a soap-cake, a lock-washer 35 on the projecting end of the shank and having an anchor pin adapted to be pressed into the soap-cake, a cap adapted to receive said washer and having screw-threaded engagement with the projecting end of the 40 shank, a pawl and ratchet connection be-

tween the cap and lock-washer to prevent unscrewing of the cap from the shank when applied to a soap-cake, and a flexible connection for the cap.

9. A soap-cake retainer comprising an 45 anchor shank one end of which is adapted to be embedded in a soap-cake, a lock-washer on the projecting end of the shank and having an anchor pin adapted to be pressed into the soap-cake, a cap adapted to receive 50 said washer and having screw-threaded engagement with the projecting end of the shank, a pawl and ratchet connection between the cap and lock-washer to prevent unscrewing of the cap from the shank when 55 applied to a soap-cake, a gasket adapted to be interposed between the cap and soap-cake, and a flexible connection for the cap.

10. A soap-cake retainer comprising an anchor shank one end of which is adapted 60 to be embedded in a soap-cake, a lock-washer on the projecting end of the shank and having an anchor pin adapted to be pressed into the soap-cake, said washer also having a plurality of circumferentially 65 spaced ratchet teeth, a cap adapted to receive said washer and having screw-threaded engagement with the projecting end of the shank, a spring-pressed pawl carried by the cap and engageable with the ratchet 70 teeth to prevent unscrewing of the cap from the shank when applied to the soap-cake, and a flexible connection for the cap.

In testimony whereof I affix my signature in presence of two witnesses.
